UNITED STATES PATENT OFFICE.

LEONARD H. PEAVY, OF NEW YORK, N. Y.

CHAIR.

1,318,403.

Specification of Letters Patent.

Patented Oct. 14, 1919.

Application filed February 21, 1919. Serial No. 278,367.

To all whom it may concern:

Be it known that I, LEONARD H. PEAVY, a citizen of the United States, residing in the city of New York, borough of Manhattan, 5 in the county and State of New York, have invented a certain new and useful Improvement in Chairs, of which the following is a specification.

The invention relates to chairs and like 10 articles of furniture of massive appearance, as in the mission type and other bulky styles, and the object of the invention is to utilize the spaces in such chair and provide therein a talking machine 15 mechanism with the records therefor, and a sound conduit performing the function of the usual horn, all such parts adapted to be easily conditioned for service by the occupant of the chair, or to be dismounted 20 and concealed in the latter when desired.

The invention consists in certain novel 25 features of construction, and arrangements of parts by which the above objects are attained, to be hereinafter described and claimed.

The accompanying drawings form a part of this specification and show an approved means of carrying out the invention.

Figure 1 is a perspective view showing 30 the framework of the back and one side or arm of a chair constructed in accordance with the invention, the cushions, upholstery and certain panels being omitted.

Fig. 2 is a similar view of the front and 35 other side or arm of the chair.

Fig. 3 is a vertical section through the upper portion of one arm, showing the 40 turntable of the phonograph in elevation.

Fig. 4 is a vertical section showing a form of universal joint between the tone-arm and sound conduit or horn.

Similar letters of reference indicate the same parts in all the figures.

A is the framework of the back of a chair 45 of a style similar to that known as "Morris," B the framework of the broad deep arm forming one side, C the similar frame for the other arm and side, and D the seat frame.

50 In the space within the arm B and preferably secured to the under face of the board B¹ forming the top or arm-rest thereof, is a casing F containing a talking machine mechanism which may be understood as operated by an electric motor.

The turntable shaft F¹ projects through the board B¹ into an opening provided for the purpose in the arm-cushion B², as in Fig. 3. The shaft is designed to receive a removable turntable F² adapted to carry 60 a record as usual. G is a switch-box in the same space beneath the board B¹, operated by push-buttons G¹ G² on the front of the arm B.

H is a hollow wing extending from the 65 arm B to the top of the back A, forming part of the latter and adapted to be upholstered or cushioned, and having a vertical door H² which may be opened to permit access to the interior. H¹ is a similar wing 70 on the arm C, which may be similarly equipped and the inclosed space utilized but is shown as permanently closed.

Mounted on the board B¹ within the wing H is a thimble L extending through the 75 board and receiving at its lower end the throat J¹ of a sound conduit J extending downwardly and transversely of the chair in the space within the back and in rear of the seat D, terminating in a rectangular 80 opening c beneath the wing H¹ and closed by a door J².

Within the thimble L is a step or bearing L¹ for a short vertical stud L² having oppositely extending spurs L³ L³ at its upper 85 end, serving as pivots for the tone-arm K, curved upwardly from the thimble and when in service extended forwardly along the arm B, with its sound-box K¹ presented in proper position relatively to the turntable F² to play a disk record upon such table.

The shaft L² and its spurs L³, with the step L¹ permit the lateral swing of the tone-arm required in following the record groove, 95 and also permit the tone-arm to be swung upwardly on the pivots L³ into the hollow wing H and be concealed therein by closing the door H².

The board C¹ forming the top of the opposite chair-arm C is hinged at the outer edge as at c¹ and serves as a lid or closure for a large recess in such arm adapted to receive the turntable F² and a supply of records.

The chair may be paneled, upholstered 105 and cushioned to present the usual appearance of such articles of furniture, and it may be of any shape or style adaptable to the purpose. By the construction and arrangement shown, an invalid or other occu- 110

pant of the chair, without change of position or undue exertion, may condition the talking machine for service and for the entertainment of himself and others.

5. I claim:—

1. The chair described having an arm, a recess beneath said arm adapted to contain the motor mechanism of a talking machine with its table-shaft extended upwardly through said arm and arranged to carry a turntable above said arm, the back of said chair having a recess to contain a tone-arm adapted to coact with said turntable.

2. The chair described having an arm, back, and seat, a recess beneath said arm adapted to contain the motor mechanism of a talking machine with its table-shaft extended upwardly through said arm and arranged to carry a turntable above said arm, a recess in said back arranged to contain a tone-arm adapted to coact with said turntable, and a sound conduit extending transversely of said chair in said back and in rear of said seat and leading from said tone-arm.

3. The chair described having an arm, back, and seat, said arm adapted to support the turntable of a talking machine, a wing on said back having a recess therein adapted to contain a tone-arm arranged to coact with said turntable and to swing upwardly into such recess, and a door for the latter whereby said tone-arm is concealed in said recess.

35. 4. The chair described having arms, back, and seat, one of said arms adapted to sup-

port the removable turntable of a talking machine, the other of said arms having a hinged lid and adapted to receive said turntable and the records therefor in a recess beneath said lid, a sound conduit extending downwardly and transversely of said chair and having a door for closing the outlet opening of said conduit, and a tone-arm arranged to coact with said turntable and leading to said conduit.

5. The chair described having an arm, back, and seat, said arm adapted to support the turntable of a talking machine, a sound conduit in said back in rear of said seat, a wing on said back, a tone-arm connected to said conduit and mounted to swing horizontally to coact with a record on said turntable, and to swing vertically into a recess in the said wing, and a door on the latter for closing such recess and concealing said tone-arm.

6. The combination of a chair having a recess in its arm, of a talking machine motor mechanism contained in such recess, with the table-shaft extending vertically through said arm and adapted to carry a removable turntable above said arm, a sound conduit leading from the rear portion of said arm downwardly and transversely of said chair in the back thereof, a tone-arm for said turntable jointed to the inlet of said conduit, and arranged to swing upwardly and lie concealed in said back.

In testimony that I claim the invention above set forth I affix my signature.

LEONARD H. PEAVY.
